TO CONTINENTAL MOTORS CORPORATION, OF DETROIT, MICHIGAN, A CORPORATION
OF VIRGINIA

METHOD AND APPARATUS FOR SHIPPING ENGINES

Original application filed April 11, 1927, Serial No. 182,557. Divided and this application filed September 20, 1928. Serial No. 307,104.

This invention relates to loading and unloading methods and apparatus and refers more particularly to an improved method and apparatus for shipping engines such as 5 internal combustion engines.

Heretofore it has been customary in shipping engines in freight cars and other conveyances to construct individual crates ordinarily made of wood, for each engine. This 10 practice involves considerable expense in lumber cost as well as in labor in constructing the crates, placing the engines in the crates and generally handling the crates both at the shipping end and at the receiving end 15 or destination. Aside from the cost of the lumber many of the crates are broken and otherwise damaged by general depreciation.

A further expense and difficulty under the practice heretofore resides in checking up 20 the crates shipped. Frequently the crates are not returned to the shipper and a check up must be made to determine such a situation. The crates frequently are damaged in removing the engines and the period of 25 usefulness of a crate is relatively short, i. e. only a relatively few number of shipments, the consignee often being charged for lost and damaged crates. Hence under the past practice of shipping engines considerable 30 expense is incurred both to the consignor and consignee.

Our invention provides a novel method and apparatus for eliminating the individual crates for the engines and generally materially reduces the labor and material costs 35 involved both to the consignor and consignee.

A further feature of our invention resides in providing novel means for securely locating the engines in place in a freight car or other conveyance whereby the engines may be closely nested and securely fixed against accidental displacement during shipment, and yet may be quickly and conveniently 40 removed from the freight car at the destination.

One advantage resulting from this feature of our invention resides in the ability to so closely nest the engines that the established minimum load per car may be obtained without decking the motors. Heretofore, in order to receive the full benefit of the shipping cost per car it was often necessary to deck the crated engines since the crates took up a relatively great amount of the available floor space of the freight car. 50

With the above and other objects in view our invention further resides in the novel combination and arrangement of parts more particularly hereinafter described.

This application is a division of our co-pending application Ser. No. 182,557, filed April 11, 1927. 60

Referring to the accompanying drawings in which like reference characters indicate corresponding parts, 65

Fig. 1 is a perspective view of the interior of a freight car illustrating one manner of shipping engines according to our invention,

Fig. 2 is a like view at right angles to Fig. 1, 70

Fig. 3 is a view corresponding to Fig. 1 illustrating a modified form of our invention, and

Fig. 4 is a view of the modification corresponding with Fig. 2. 75

In the drawings reference character A represents a typical freight car, such as ordinarily used for shipping engines and other articles, 10 representing the floor, 11 the end walls, 12 the side walls, and 13 the doors and door openings. 80

In carrying out our invention we may provide a travelling engine hoist apparatus C more particularly described and claimed in our aforesaid co-pending application. 85 Thus the hoist C may be movable to any part of the car by reason of the rollers 25 operating on track 23 which, in turn, is movable longitudinally of the car by reason of the spaced supporting rails 22. By 90

reason of our travelling hoist apparatus C the engines B may be readily and quickly loaded into the freight car or unloaded therefrom. The particular operation or construction of such loading apparatus forms 5 no part of this application and any desired suitable apparatus may be employed.

A feature of our invention resides in the manner of nesting, locating, and securing 10 the engines in position within the cars. Referring to Figs. 1 and 2 the engines are placed in position as by our loading apparatus, upon spaced supports 33, preferably of wood extending transversely across the 15 floor of the car, the ends of the supports 33 being properly spaced according to the longitudinal dimension of the engine by the spacers 34 secured as by nails to the supports 33. In order to prevent displacement 20 of the supporting units formed by the members 33 and 34, unit spacers 35 may be provided. To further securely fix the engines in position end boards 36 may be placed at the ends of each transverse 25 row of engines across the supports 33 and adjacent the end engines of each row. As shown in Fig. 1 engine spacing blocks 37 may be located between adjacent engines of each row, these blocks for convenience 30 being located below upper positioning boards 38 overlying each row of engines. We next tie the engines of each row together by passing a tie member, wire, or metal strip 39 preferably entirely around 35 the engines of each row, fixing the ends of the tie member in any convenient manner. Next, other ties 40 are passed preferably at several points along the length of each row 40 of engines taking up any slack in the tie member 39 and serving to further secure the engines in position. It is generally desirable to pass the ties 40 beneath the supports 33 and above the boards 38, these ties for convenience being placed on the floor 45 of the car before placing the supports 33. In this manner the engine supports 33 may be quickly placed in position, the engines then being positioned by the loading apparatus, followed by placement of the boards 50 and the ties. If desired the boards 33 may have their upper faces grooved to receive the engines, the grooves corresponding in general with the lower shape of the engine.

Instead of positioning the unit rows of 55 engines transversely of the car, these rows might also be formed longitudinally of the car as shown in Figs. 3 and 4. In these views the supports 33' and upper boards 38' extend longitudinally of the car, ties 60 39' and 40' being employed substantially as described above with reference to Figs. 1 and 2. In Fig. 3 we have shown the ties 39' extending longitudinally of the car, passing around the engines of each row respectively.

In unloading the cars the ties and upper boards are removed, the apparatus shown in Fig. 1 being employed to remove the engines from the cars. If desired the loading and unloading apparatus may be left 70 in the car during shipment or may be built permanently in the car.

Our invention provides means for securely fixing the engines in position without the use of individual crates used heretofore. Furthermore a saving is made possible in the elimination of much of the lumber used heretofore in crates as well as crate losses and deterioration expenses. With our invention the engines may be closely 80 nested, making it possible to obtain the minimum required load in a freight car without the necessity of decking the engine. 85

We do not limit ourselves to the particular apparatus and arrangement of engine 90 location as shown and described as it is apparent that many changes may be resorted to and still utilize the benefits of our invention. We believe our invention to be of a very broad scope since we are aware of no 95 method or apparatus making it possible heretofore to ship motors without the use of the individual crates. 100

What we claim as our invention is:

1. Means for grouping internal combustion engines for shipment in freight cars comprising a frame support mounted within the car for receiving a plurality of engines, a member overlying the engines, and flexible material wound about the frame and said member for preventing relative movement of the engines during shipment. 105

2. Means for grouping internal combustion engines for shipment in freight cars comprising a frame support mounted within the car for receiving a plurality of engines, a member overlying the engines, and flexible material wound about the frame and said member, and also about the engines for preventing relative movement of the engines 110 during shipment. 115

3. Means for grouping internal combustion engines for shipment in freight cars comprising a frame support within the car, said support formed of members extending substantially longitudinally and transversely respectively of the car, said engines being mounted on said frame, means overlying the engines, and flexible tie means connecting the frame support and overlying means serving to prevent relative displacement of the engines during shipment. 120

4. Means for grouping internal combustion engines for shipment in freight cars comprising a frame support within the car, said support formed of members extending substantially longitudinally and transversely respectively of the car, said engines being mounted on said frame, with their longest dimensions extending longitudinally of the 125 130

car, means overlying the engines in a direction transverse to the longest dimension aforesaid, and flexible tie means connecting the frame support and overlying means serving to prevent relative displacement of the engines during shipment.

5. The method of grouping and relatively securing internal combustion engines for shipment in freight cars consisting in providing a plurality of engine group supports extending transversely of the car, mounting said engines on said supports respectively with the longest dimension of the engines transverse to the supports and in the longitudinal direction of the car, and tying the engines to said respective supports to prevent their displacement in transit.

6. The method of grouping and relatively securing internal combustion engines for shipment in freight cars consisting in providing a plurality of engine group supports extending transversely of the car, mounting said engines on said supports respectively with the longest dimension of the engines transverse to the supports and in the longitudinal direction of the car, and tying the engines to each other relatively in groups and to the said respective supports to prevent displacement of the engines in transit.

30 7. The method of grouping and relatively securing internal combustion engines for shipment in freight cars consisting in providing a plurality of engine group supports extending transversely of the car, mounting said engines on said supports respectively with the longest dimension of the engines transverse to the supports and in the longitudinal direction of the car, overlying the engines of each group with a stiffening member extending parallel with the supports, and tying the supports, engines, and stiffening members as units against relative displacement in transit.

8. The method of grouping and relatively securing internal combustion engines for shipment in freight cars consisting in providing a plurality of engine group supports, mounting said engines on said supports, and tying the engines to said supports in groups to prevent relative displacement of the engines of any group.

9. The method of grouping and relatively securing internal combustion engines for shipment in freight cars consisting in providing a plurality of engine group supports, mounting said engines on said supports with the longest dimension of the engines transverse to said supports, and tying the engines to each other relatively in groups and to said supports to prevent relative displacement of the engines of any group.

10. The method of grouping and relatively securing internal combustion engines for shipment in freight cars consisting in providing a plurality of engine group supports,

mounting said engines on said supports with the longest dimension of the engines transverse to said supports, overlying the engines of each group with a stiffening member extending parallel with the supports, and tying the supports, engines, and stiffening members as units against relative displacement in transit.

In testimony whereof, we hereunto affix our signatures, this 8th day of Sept., A. D. 1928.

GUSTAV L. LUNDBORG.
RICHARD B. ISRAEL.
